UNITED STATES PATENT OFFICE.

THOMAS VEITCH, OF DUMONT, NEW JERSEY, ASSIGNOR TO WALTER S. THOMSON, OF NEW YORK, N. Y.

INTERNAL-COMBUSTION ENGINE.

1,009,945.

Specification of Letters Patent. Patented Nov. 28, 1911.

Application filed May 25, 1910. Serial No. 563,374.

To all whom it may concern:

Be it known that I, THOMAS VEITCH, a citizen of the United States, and a resident of Dumont, in the county of Bergen and State of New Jersey, have invented certain new and useful Improvements in Internal-Combustion Engines, of which the following is a specification.

The present invention relates to improvements in internal combustion engines, and more particularly to means for admitting one or more of the constituents of the combustible charge to the compression chamber of the engine.

One of the objects of the invention is to provide a valve construction for controlling, while the engine is running, the admission of the combustible charge, or of one or more of its constituents, to the crank-case in such a manner that the point of admission and the point of the cutoff of the charge entering the compression chamber of the engine may be predetermined and varied at will, so as to control thereby the speed and power of the engine.

Another object of the invention is to construct a valve mechanism for a reversible two cycle engine which is very simple in construction, efficient and reliable in operation, consisting of very few parts of simple design and possessing the features above mentioned.

With these and other objects in view, which will more fully appear as the nature of the invention is better understood, the same consists in the construction, arrangement and combination of the several parts hereinafter fully described, pointed out in the appended claims and illustrated in the accompanying drawings, it being understood that various changes may be made in the size, proportion and construction of parts without departing from the spirit or sacrificing any of the advantages of the invention.

One of the many possible embodiments of the invention is illustrated in the accompanying drawings, in which:

Figure 1 is a side elevation of an engine constructed in accordance with the present invention, the supply pipe being removed to more clearly show the interior parts; Fig. 2 is a section taken on line 2—2 of Fig. 1; Fig. 3 is a diagrammatic view of the valve construction, showing the parts in the positions indicated in Fig. 1 of the drawings;

Figs. 4 and 5 are diagrammatic views of the valve mechanism showing the parts in different positions from that shown in Fig. 3; Figs. 6 and 7 are diagrammatic views of modified constructions of the valve showing the parts in two different positions, and Fig. 8 is a section taken on line 8, 8 of Fig. 6.

Referring now more particularly to Figs. 1 to 5, inclusive, the numeral 10 designates the cylinder of the engine, having, in the case shown, the usual water-jacket 11, and being mounted upon the crank-case 12, which is provided with the usual bearings 13 and 14, in which the crankshaft 15 is journaled. The webs of the crank are denoted by the numerals 16, 16. The wrist-pin is shown at 17, and is connected by means of the piston-rod 18 with the piston 19, which is provided with the usual deflector 20. A transfer passage 21 connects the interior of the crank-case with the inlet port 22 of the cylinder, opposite to which is arranged the exhaust port, from which the exhaust pipe 23 leads in the usual manner. Upon the crankshaft is mounted a fly-wheel 24 for well known reasons. Thus far the construction and operation of the engine do not differ in any essential way from the engine heretofore in use.

Upon the side 25 of the crank-case 12 is arranged a chamber 26, to which leads a supply pipe 27 conducting to the said chamber either the combustible charge, or air, if the engine is provided with a fuel injection device. This chamber communicates with the interior of the crank-case through an arc-shaped opening 28, which extends over an angular distance of about 180° for a purpose to be hereinafter described. The communication between the chamber 26 and the interior of the crank-case is controlled by a rotary valve 29, which comprises a substantially horse-shoe shaped disk attached to one of the webs 16 of the crank-case, by having fixedly attached to said rotary valve studs 30, 30, which fit the bores, 31, 31 in said web. Springs or other resilient means 32 bear against the valve 29 and the crank web, and tend to force the said rotary valve against the inner surface of the crank-case side 25, providing thereby a substantially airtight closure therebetween. The radially arranged straight edges 33 and 34 of the rotary valve 29 are located about 90° apart, and form the

opening and closing edges, respectively, of the valve, as will be hereinafter more fully described.

In the inner surface of the side of the 5 crank-case is provided an annular groove 35, which is arranged concentrically with the opening 28 in the crank-case side. In this groove are shiftably mounted two independent ring segments 36 and 37, which are provided upon their outer peripheral portions 10 with teeth 38 and 39, respectively, meshing with pinions 40 and 41, respectively, which pinions are mounted upon shafts 42 and 43, adapted to be operated from the outer side 15 of the crank-case. The ring segment 36 serves to determine the point of admission of the charge or one of its constituents to the crank-case, while the ring segment 37 is adapted to control that point at which the 20 admission of the gas supply or air ceases. The two ring segments form thus in fact a cut-off valve. The segment 36, which controls the admission, extends through an angular distance of about 90° , and is adapted 25 to move through a comparatively small angle in its groove, as the point of admission of the fuel should be always near the lower dead center of the crank. The segment 37 is of greater angular length than the segment 30 36 and is arranged to move through a greater angular distance, whereby the entering charge may be cut off very shortly after its point of admission, or may be allowed to enter the crank-case throughout the entire 35 upward stroke of the piston and for some distance over the upper dead center of the crank, or in other words throughout the entire time through which vacuum is present in the crank-case, or the charge may enter 40 the crank-case for any time between these two limits.

The operation of the device is as follows: As the crankshaft rotates, the combustible charge or one of its constituents will be admitted 45 into the crank-case as soon as the opening edge 33 of the rotary valve 29 passes the edge 36' of the segment 36, and such admission will last until the closing edge 34 of the rotary valve 29 passes the edge 37' of the segment 37, if the engine is running in the direction of the arrow indicated in Fig. 1 of the drawings. If the segments 36 and 37 are shifted by the pinions 40 and 41 into the positions shown in Fig. 3 of the drawings, the combustible charge or one of its constituents will be admitted into the crank-case during the entire upward stroke of the piston. The rotary valve begins to open at the point marked by the line I and the cut-off occurs at the line marked II. The angular distance between the lines I and II plus the angular distance between the edges 50 33 and 34 of the rotary valve is equal to about 180° and corresponds to the upward 55 travel of the piston. The opening edge 33

of the rotary valve passes the edge 36' of the segment 36 when the crank is in its lower dead center and the closing edge 34 of the rotary valve passes the edge 37' of the segment 37 when the crank is about in its upper 70 dead center. The position shown in Fig. 3 may be termed "the normal or central position" of the valve mechanism.

In shifting the segment 37 almost into contact with the segment 36, as shown in 75 Fig. 4 of the drawings, the admission will begin when the crank has just passed its lower dead center and is in the position III, and will cease at position IV, that is at a point before vacuum in the crank-case has 80 been sufficiently formed, whereby only a very small charge will be admitted into the crank-case. In moving the segment 37 so that its edge 37' contacts with the edge 36' of the segment 36, the opening 28 is entirely 85 closed and the engine will come to rest. In shifting, however, the segment 37 so that it uncovers the opening 28 in the crank-case side to a large extent, for instance, as shown in Fig. 5 of the drawings, the admission will 90 begin after the crank has passed the lower dead center, after reaching the position shown by the dotted line marked V, and the communication between the supply of fuel or one of its constituents and the crank-case 95 will be closed when the crank center passes dotted line marked VI, that is after it has passed considerably the upper dead center. Obviously a full opening of the valve is thus obtained during the time of the most 100 effective vacuum in the crank-case. If the segments 36 and 37 are shifted so that their edges 36' and 37' coincide with straight edges 28' and 28'' of the opening 28, the 105 communication between the supply of fuel or air and the crank-case will remain open during almost three-fourths of a revolution 110 of the crankshaft.

It is obvious that for every given load and speed of the engine, a particular charge 110 is required for the same. The best result is obtained for both low and high speeds, of course, if the point of admission and the point of cut-off of the charge can be varied relative to the crank while the engine is 115 running. With the device herein described, the admission to and cut-off of the charge or one of its constituents in two cycle engines can be governed so that the engine can be 120 throttled and run quietly on light loads, and a greater charge can be admitted for full loads and high speeds.

While in Figs. 3, 4 and 5 three positions of the device have been shown, it will be easily seen that the segments may be set to any intermediate positions, which may be required for the change in speed and load. The ring segments may be set by hand, or they may be shifted by a governor into the 125 most effective position necessary to the most 130

satisfactory operation of the engine both for speed and power.

A modification of the device is shown in Figs. 6 to 8, inclusive, which controls the admission of the charge to the crank-case, and is adapted at the same time to reverse the direction of rotation of the engine by a very simple operation. The crank-case side 45 is provided in this case with a recess 46, 10 to which leads a cylindrical opening 47 in communication with the supply of fuel or with the air, as the case may be. A groove 48 is formed concentrically with the recess 46, and in this groove are arranged the ring 15 segment 49 for controlling the point of admission of the charge and the ring segment 50 for controlling the point of cut-off of the charge. A projection 51 is formed on the inner face of the ring segment 49, fitting 20 snugly the recess 46 and dividing thus the same into two non-communicating sections.

If it is intended to run the engine in the direction of the arrow shown in Fig. 6 of the drawings, the projection 51 upon the 25 segment 49 is shifted together with the segment 49 so that the projection comes to lie on the right-hand side of the opening 47. The edge 49' forms then the opening edge of the cut-off valve and the edge 50' of the 30 segment 50 the closing edge. In order to reverse the direction of rotation of the engine, the projection 51 is brought to the left-hand side of the opening 47, as shown in Fig. 7 of the drawings, when the edge 49'' 35 of the segment will form the opening edge of the cut-off valve. The segment 50 is then set so that its edge 50'' occupies the desired position, that is to say either an advance or throttle position, or any other intermediate position.

While herein certain relations between the size of the opening in the crank-case and the distance between the straight edges of the rotary valve have been specified, and a 45 particular arrangement, sizes and forms of the cut-off valve portions have been shown and described, it will be easily seen that the relations, sizes and forms mentioned may be varied according to the requirements, and 50 the device will still come within the scope of the appended claims, as the invention lies mainly in the combination of a rotary valve with a cut-off valve comprising a structure, whereby the point of admission and the 55 point of the cut-off of the charge may be predetermined and varied according to the conditions at hand. The rotary valve may, of course, be operated by means connected directly or indirectly with the crankshaft. 60 Obviously instead of the horseshoe-shaped rotary disk a slotted rotary disk may be made use of.

What I claim is:

1. In an internal combustion engine, the 65 combination with the compression chamber

of the engine having an opening in one of its walls, of a rotary valve adapted to control the communication between said opening and the interior of said chamber, and means varying, at will, independently of each other both the points of opening and closing of said communication relative to the cycle of operation within the cylinder of the engine. 70

2. In an internal combustion engine, the combination with the compression chamber 75 of the engine having an opening in one of its walls, of a rotary valve adapted to control the communication between said opening and the interior of said chamber, and means interposed between said opening and said valve varying, at will, independently of each other both the points of opening and closing of said communication relative to the cycle of operation within the cylinder of the engine. 80

3. In an internal combustion engine, the combination with the compression chamber of the engine having an opening in one of its walls, of a rotary disk adapted to control the communication between said opening 90 and the interior of said chamber, and means for varying, at will, independently of each other both the points of opening and closing of said communication relative to the cycle of operation within the cylinder of the 95 engine.

4. In an internal combustion engine, the combination with the compression chamber of the engine having an opening in one of its walls, of a rotary disk adapted to control the 100 communication between said opening and the interior of said chamber, and means interposed between said opening and said disk for varying, at will, independently of each other both the points of opening and closing of said communication relative to the cycle of operation within the cylinder of the 105 engine.

5. In an internal combustion engine, the combination with the crank-case of the engine having an opening in one of its walls, 110 of a crankshaft arranged in said crank-case, a rotary valve attached to said crankshaft adapted to control the communication between said opening and the interior of said crank-case, and means varying, at will, independently of each other both the points of opening and closing of said communication relative to the cycle of operation within the cylinder of the engine. 115

6. In an internal combustion engine, the combination with the crank-case of the engine having an opening in one of its walls, 120 of a crankshaft arranged in said crank-case, a rotary valve attached to said crankshaft adapted to control the communication between said opening and the interior of said crank-case, and means interposed between said opening and said valve varying, at will, independently of each other both the points 125

of opening and closing of said communication relative to the cycle of operation within the cylinder of the engine.

7. In an internal combustion engine, the combination with the crank-case of the engine having an opening in one of its walls, of a crankshaft arranged in said crank-case, a rotary disk attached to said crankshaft adapted to control the communication between said opening and the interior of said crank-case, and means for varying, at will, independently of each other both the points of opening and closing of said communication relative to the cycle of operation within the cylinder of the engine.

8. In an internal combustion engine, the combination with the crank-case of the engine having a casing in one of its walls, of a crankshaft arranged in said crank-case, a rotary disk attached to said crankshaft and adapted to control the communication between said opening and the interior of said crank-case, and means interposed between said opening and said disk for varying, at will, independently of each other both the points of opening and closing of said communication relative to the cycle of operation within the cylinder of the engine.

9. In an internal combustion engine, the combination with the compression chamber of the engine having an opening in one of its walls, of a rotary valve adapted to control the communication between said opening and the interior of said chamber, and means independent of said valve for predetermining and varying the size of said opening and the angular relation of the opening and closing points of said communication relative to the crank of the engine.

10. In an internal combustion engine, the combination with the compression chamber of the engine having an opening in one of its walls, of a rotary valve adapted to control the communication between said opening and the interior of said chamber, and means interposed between said opening and said valve for predetermining and varying the size of said opening and the angular relation of the opening and closing points of said communication relative to the crank of the engine.

11. In an internal combustion engine, the combination with the compression chamber of the engine having an opening in one of its walls, of a rotary disk adapted to control the communication between said opening and the interior of said chamber, and means for predetermining and varying the size of said opening and the angular relation of the opening and closing points of said communication relative to the crank of the engine.

12. In an internal combustion engine, the combination with the compression chamber of the engine having an opening in one of its

walls, of a rotary disk adapted to control the communication between said opening and the interior of said chamber, and means interposed between said opening and said disk for predetermining and varying the size of said opening and the angular relation of the opening and closing points of said communication relative to the crank of the engine.

13. In an internal combustion engine, the combination with the crank-case of the engine having an opening in one of its walls, of a crank shaft arranged in said crank-case, a rotary valve attached to said crank shaft adapted to control the communication between said opening and the interior of said crank-case, and means for predetermining and varying the size of said opening and the angular relation of the opening and closing points of said communication relative to the crank of the engine.

14. In an internal combustion engine, the combination with the crank-case of the engine having an opening in one of its walls, of a crankshaft arranged in said crank-case, a rotary valve attached to said crank-shaft adapted to control the communication between said opening and the interior of said crank-case, and means interposed between said opening and said valve for predetermining and varying the size of said opening and the angular relation of the opening and closing points of said communication relative to the crank of the engine.

15. In an internal combustion engine, the combination with the crank-case of the engine having an opening in one of its walls, of a crankshaft arranged in said crank-case, a rotary disk attached to said crank-shaft adapted to control the communication between said opening and the interior of said crank-case, and means for predetermining and varying the size of said opening and the angular relation of the opening and closing points of said communication relative to the crank of the engine.

16. In an internal combustion engine, the combination with the crank-case of the engine having an opening in one of its walls, of a crankshaft arranged in said crank-case, a rotary disk attached to said crank-shaft and adapted to control the communication between said opening and the interior of said crank-case, and means interposed between said opening and said disk for predetermining and varying the size of said opening and the angular relation of the opening and closing points of said communication relative to the crank of the engine.

17. In an internal combustion engine, the combination with the compression chamber of the engine having an opening in one of its walls, of a rotary valve adapted to con-

5 trol the communication between said opening and the interior of said chamber, means for varying, at will, independently of each other both the points of opening and closing of said communication relative to the cycle of operation within the cylinder of the engine.

10 18. In an internal combustion engine, the combination with the compression chamber of the engine having an opening in one of its walls, of a rotary disk adapted to control the communication between said opening and the interior of said chamber, means for varying, at will, independently of each other both the points of opening and closing of said communication relative to the cycle of operation within the cylinder of the engine.

15 19. In an internal combustion engine, the combination with the compression chamber of the engine having an opening in one of its walls, of a rotary valve adapted to control the communication between said opening and the interior of said chamber, and means for varying at will the point of opening only of said communication relative to the cycle of operation within the cylinder of the engine.

20 20. In an internal combustion engine, the combination with the compression chamber of the engine having an opening in one of its walls, of a rotary valve adapted to control the communication between said opening and the interior of said chamber, and

means interposed between said opening and 35 said valve for varying at will the point of opening only of said communication relative to the cycle of operation within the cylinder of the engine.

21. In an internal combustion engine, the 40 combination with the compression chamber of the engine having an opening in one of its walls, of a rotary disk adapted to control the communication between said opening and the interior of said chamber, and means 45 for varying at will the point of opening only of said communication relative to the cycle of operation within the cylinder of the engine.

22. In an internal combustion engine, the 50 combination with the compression chamber of the engine having an opening in one of its walls, of a rotary disk adapted to control the communication between said opening and the interior of said chamber, and 55 means interposed between said opening and said disk for varying at will the point of opening only of said communication relative to the cycle of operation within the cylinder of the engine.

60 Signed at New York, in the county of New York and State of New York, this 27th day of May, A. D. 1910.

THOMAS VEITCH.
